UNITED STATES PATENT OFFICE.

DAVID S. KENNEDY, OF BROOKLYN, NEW YORK, ASSIGNOR TO MERGEN-
THALER LINOTYPE COMPANY, A CORPORATION OF NEW YORK.

LINOTYPE-MACHINE.

No. 810,153.

Specification of Letters Patent.

Patented Jan. 16, 1903.

Application filed February 3, 1905. Serial No. 243,955.

To all whom it may concern:

Be it known that I, DAVID S. KENNEDY, of Brooklyn, county of Kings, and State of New York, have invented a new and useful Improvement in Linotype-Machines, of which the following is a specification.

This invention has reference to the magazines employed for holding the matrices in linotype-machines of the general organization shown in United States Letters Patent No. 436,532. These magazines are constructed with longitudinal channels, in which the matrices are guided on edge. As the machines are constructed at the present day the magazines are adapted for removal, and in practice they are frequently interchanged in order to bring into use matrices of different fonts. When the magazine is removed, it is important that the matrices shall be confined therein, so that they may not be accidentally discharged at its upper end. Heretofore this result has been secured by the introduction of wooden bars temporarily within the end of the magazine and by the employment of other devices which were not permanent members of the magazine.

My invention consists in providing the end of the magazine with a covering plate or bar permanently attached thereto and adapted to turn instantly into position to cover or uncover the end.

My contrivance may be modified in form and arrangement; but I have represented herein a construction which is found in practice to fully answer its purpose.

Referring to the drawings, Figure 1 is a perspective view of the upper end of a magazine with my attachment thereon, the end being open, as when in action. Fig. 2 is a top plan view showing a locking device for the cover. Fig. 3 is a perspective view looking into the upper open end of the magazine. Fig. 4 is a perspective view of the upper end of the magazine closed by the cover-plate. Fig. 5, Fig. 6, and Fig. 7 are side views illustrating the various positions of the cover and the manner in which it is guided and secured.

Referring to the drawings, A represents the magazine consisting of parallel top and bottom plates *a a*, grooved longitudinally in their inner faces and secured at such distance apart as to admit of the matrices being inserted on edge between them, as shown in Fig. 3. The object in view is to close the up-

per end of this box-like magazine to prevent the accidental escape of the matrices or the entrance of dust and foreign bodies, and this by means of a cover permanently attached and adapted to be set instantly in operative position or in an inoperative position, in which it shall not interfere with the operation of the machine.

B represents my cover-plate or lid consisting simply of a flat bar of suitable size to cover the end of the magazine, as shown in Fig. 4, with its two ends bent backward at right angles in order to rest against the edges or sides of the magazine, as shown. These parallel ends are provided with diagonal slots *b* to receive studs *b'*, seated in the sides of the magazine and serving as permanent connections between the magazine and the cover. It is required to have the cover-plate B turn from the position shown in Figs. 4 and 7 upward on top of the magazine in the manner shown in Figs. 1, 3, and 5, so as to leave the end of the magazine unobstructed. In order to assist in guiding the plate in its movements, its ends or arms are provided each with a second groove *b''*, curved, as shown, and adapted to receive a stud *b''*, seated in the side of the magazine. The two grooves and the studs guide the cover in its turning movement, as shown in Figs. 5, 6, and 7, causing it to be seated in one position snugly on top of the magazine and in the other position snugly over the end of the magazine, holding it in each of said positions. Knobs or handles *b''* are preferably applied to the cover as a convenient means of operating the same.

It is preferable, although not necessary, to provide means for locking the cover, particularly when in the closed position. I therefore apply to either or both sides of the magazine a spring C, having one end secured by screws *c* and the opposite end provided with a stud *c'* to enter corresponding holes in the cover. When the cover reaches either of its two positions, the spring will snap into place and prevent it from being moved except by the exertion of considerable force, whereupon the beveled stud *c'* will ride automatically out of its seat.

A cover device applied as herein shown serves to secure the matrices within the magazine and to exclude dust and dirt therefrom. Owing to its form, it offers no obstruction to the removal of the magazine edgewise from the

machine, nor does it project in such manner as to interfere with the convenient handling of the magazine or with its introduction edge-wise into a rack or holder. The attachment 5 of the cover to the magazine at the edges or sides as shown is advantageous, in that it permits the parts to be constructed without any joints or other parts projecting or protruding above the surface of the magazine. 10 Consequently the magazines presenting smooth unobstructed surfaces may be readily stacked upon each other and stored into racks or otherwise handled in a manner not otherwise possible. The location of the connecting studs or pivots is such that if the magazine is overturned and the weight of the matrices thrown against the inside of the cover B the latter has no tendency to open. 15 In other words, there will be no tendency of the top to swing open, as in the case of a top or lid hinged along one edge to a magazine. The extension of the ends of the cover B rearward over the edges of the magazine and their attachment thereto is also advantageous, 20 in that the weight or thrust of the matrices against the cover in the event of the magazine being overturned applies a longitudinal strain to the cover, which is prevented from bending by reason of its ends overlapping the edges of the magazine. This fact 25 permits the use of a cover much thinner and lighter than would otherwise be admissible. It is to be noted that my cover is in the 30 form of a solid plate adapted to tightly close the upper end of the magazine, so as to prevent the escape of the matrices and also prevent the entrance of dust. It is to be further noted that the mode of hinging or joining this plate to the magazine admits of its 35 being turned down compactly against the top of the magazine when open, so that it will

not interfere with the entrance-throat through which the matrices enter the magazine or the usual hinged plate thereon.

Having described my invention, what I 45 claim is—

1. The channeled linotype-magazine, in combination with the plate, B, adapted to cover and close the end of the magazine, said plate united to the magazine by sliding and turning end connections, substantially as shown, adapted to confine the plate against the end and also to permit it to lie closely upon the outside of the magazine when open. 50

2. The combination of a linotype-magazine with a cover-plate having angular ends, each end connected with the edge of the magazine by two slots and studs constructed substantially as shown, to permit the cover to be closed tightly over the end of the magazine or to be opened flatly against its side face. 60

3. In combination with the channeled magazine, the closing-plate having angular ends extended along the edges of the magazine and connected thereto by studs, substantially as shown, whereby the plate is adapted to fold against the outer surface of the magazine, and also adapted to close its end and to resist the escape of the matrices. 65 70

4. A linotype-magazine in combination with a cover-plate having angular ends, studs and slots connecting said parts, and a spring-catch to hold the cover in operative position.

In testimony whereof I hereunto set my 75 hand, this 26th day of January, 1905, in the presence of two attesting witnesses.

DAVID S. KENNEDY.
